UNITED STATES PATENT OFFICE.

CHARLES C. SPREEN, OF DETROIT, MICHIGAN, ASSIGNOR TO KELVINATOR CORPORATION, OF DETROIT, MICHIGAN, A CORPORATION OF MICHIGAN.

REFRIGERATION.

Application filed February 21, 1927. Serial No. 169,757.

My invention relates to refrigeration, and particularly to means for increasing the heat absorbing power of a refrigerant expansion unit, and the principal object of my invention is to provide new and improved means of this type. In the drawings accompanying this specification and forming a part of this application I have shown, for purposes of illustration, one form which my invention 5 may assume, and in these drawings:

Figure 1 is a front elevation of this embodiment of my invention, while

Figure 2 is a side elevation thereof.

The embodiment of my invention shown 15 herein comprises a receptacle 11 adapted to contain brine or similar heat conducting material, having the form of a spiral tube and adapted to be disposed around a refrigerant expander 12, of the usual float valve type, 20 with an extended portion of each turn of the spiral depending below the expander 12 in the form of a loop 13. The space enclosed by the depending loops 13 is divided by shelves 14 attached to the sides of the loops 13 into a 25 plurality of sections adapted to receive ice trays 15 supportable on the shelves 14, and the sides of the loops 13 are also provided with outwardly extending fins 16 which serve to increase the heat conducting power of the 30 tube like receptacle 11.

From the above disclosure it will be obvious to those skilled in the art that I have provided new and improved means for increasing the heat absorbing power of a refrigerant expansion unit in a mechanical refrigeration system.

At the same time it also will be obvious to those skilled in the art that the embodiment of the invention herein shown and described 40 may be variously changed and modified without departing from the spirit of my invention or sacrificing the advantages thereof, and it therefore will be understood that the disclosure herein is illustrative only, and that my invention is not limited thereto.

I claim:

1. For use in the refrigerating compartment of a mechanical refrigerator system: a heat absorbing unit comprising a refrigerant 50 expansion drum, as of the usual float type, and heat conducting means, for increasing the heat absorbing power of said drum, having the form of a spiral tube adapted to contain brine, having with said brine a high heat 55 conductivity, engaged about the exterior of

said drum, extending substantially throughout the length of said drum, and extending outwardly from said drum.

2. For use in the refrigerating compartment of a mechanical refrigerator system: a 60 heat absorbing unit comprising a refrigerant expansion drum, as of the usual float type, and heat conducting means, for increasing the heat absorbing power of said drum, having the form of a spiral, having a high heat 65 conductivity, engaged about the exterior of said drum, extending substantially throughout the length of said drum, extending outwardly from said drum, and provided with supporting means adapted to support objects 70 such as ice trays.

3. For use in the refrigerating compartment of a mechanical refrigerator system: a heat absorbing unit comprising a refrigerant expansion drum, as of the usual float type, 75 and heat conducting means, for increasing the heat absorbing power of said drum, having the form of a spiral tube, adapted to contain heat conducting material, having with said material a high heat conductivity, engaged about the exterior of said drum, extending substantially throughout the length 80 of said drum, extending outwardly from said drum, and provided with supporting means adapted to support objects such as ice trays. 85

4. In a mechanical refrigerating system, a cooling unit including a liquid refrigerant container, and a continuous brine containing coil extending around and having regularly spaced portions of the length thereof engaging said container.

5. In a mechanical refrigerating system, a cooling unit including a liquid refrigerant container, and brine containing pipe loops supported by said container in thermal contact therewith at one end of said loops and having the other end of said loops spaced therefrom.

6. In a mechanical refrigerating system, a cooling unit including a liquid refrigerant container, brine containing loops supported in thermal contact with said container, and fins attached to portions of said loop, disposed remote from said container, said fins being formed of high heat conducting material. 100 105

7. In a mechanical refrigerating system, a cooling unit including a liquid refrigerant container, and a continuous brine containing coil extending helically the length of said container, said coil being formed of high heat 110

- conducting material and arranged with one end of each loop of said coil in thermal contact with said container and with the other end of each loop spaced from said container.
8. In a mechanical refrigerating system, a cooling unit including a liquid refrigerant container, a brine containing coil wound spirally around said container and extending outwardly therefrom in looped form, and
- 10 tray supporting means within said outwardly extending loops.
9. In a mechanical refrigerating system, a cooling unit including a liquid refrigerant container, brine containing pipe loops in thermal contact with said container and extending from one side thereof in aligned relation, and a tray supporting shelf within and secured in thermal contact with the opposite legs of said loops.
- In testimony whereof I hereunto affix my signature.

CHARLES C. SPREEN.
